Inventor:

L. G. Neumar

UNITED STATES PATENT OFFICE.

LEWIS GERARD NEUMAR, OF CHICAGO, ILLINOIS.

ASH SIFTER.

Application filed March 17, 1922. Serial No. 544,474.

To all whom it may concern:

Be it known that I, LEWIS GERARD NEUMAR, a citizen of the United States, residing at Chicago, in the county of Cook and 5 State of Illinois, have invented a new and useful Ash Sifter, of which the following is a specification.

My invention relates to improvements in ash sifters in that it is used right in the 10 stove in connection with the ash pan. It is composed of a box with outlets on the bottom, sides and ends, and rests in the ash pan to receive the coal and ash when the fire is dumped and then to be sifted, the ash falling 15 through the outlets on the bottom, sides and ends into the ash pan and the ashless burnable coal remaining in the receiver to be put into a coal bucket and then into the fire again as needed.

20 I attain these results as illustrated in the accompanying drawing, in which—

Figure 1 is a longitudinal section; Figure 2 is a transverse section; and Figure 3 is a plan view.

25 Similar numerals refer to similar parts throughout the several views.

The lower part of the front and rear ends and sides of the sifter are punched with 30 holes, 1, and the bottom with oblong shaped openings, 2, these holes and openings serving as outlets for the ash.

The front and rear ends, 3, instead of slanting outwardly from the bottom of the sifter towards the top as the sides, 4, slightly 35 slant inwardly toward the top. This is for the reason that as the ashes are forced through the outlets, the coal and ash at the

ends gradually fall to a lower level, whereas if the ends were constructed with an outward slant toward the top the coal and 40 ash would in some cases "bunch up," by reason of the stirrer being pulled and pushed towards the ends.

The upper portion of the sides, 5, are bent in at an angle of 45 degrees, and then out 45 again, 6, to keep the ash or coal from coming over the sides when in the act of sifting.

The sifting process is accomplished by the short forward and backward movements 50 of the stirrer, 7, the stirrer working in a slide, 8, in the center of the bottom section of the sifter. The part of the stirrer protruding through the slide on the bottom, 9, will have a small hole to receive a cotter pin. 55 This will keep the stirrer at the bottom as it goes forward and backward. The stirrer rod slides in a slot, 10, in the front end. This rod can be brought through a similar slot in the door of the stove opening to the 60 ash pan, thereby eliminating all dust in the room when using the stirrer.

I claim:

An ash sifter, adapted to rest in an ash pan of a stove, having perforate upwardly 65 and outwardly slanting sides, perforate upwardly and inwardly slanting front and rear ends and a perforate bottom, a stirrer adapted to move over the bottom toward and away from the slanting ends of said sifter 70 to force ashes therethrough as and for the purpose described.

LEWIS GERARD NEUMAR.
